Inventor,
Henry P. Upham;
By
A. B. Upham,
Attorney.

UNITED STATES PATENT OFFICE.

HENRY P. UPHAM, OF MALDEN, MASSACHUSETTS.

LIQUID-SOAP SERVER.

1,412,428.

Specification of Letters Patent. Patented Apr. 11, 1922.

Application filed January 10, 1920. Serial No. 350,497.

To all whom it may concern:

Be it known that I, HENRY P. UPHAM, a citizen of the United States, and a resident of the city of Malden, in the county of Middlesex and Commonwealth of Massachusetts, have invented certain new and useful Improvements in Liquid-Soap Servers, for which the following is a full, clear, and exact specification.

10 This invention relates to that form of delivery devices for liquid soap and the like, wherein a suitable receptacle for the liquid is provided with a hand-operated means for delivering into the hand of the user a specified amount thereof. The object of this invention is the construction of a liquid serving device wherein the receptacle, the receptacle supporting means and the delivery instrumentality shall be of maximum cheapness to manufacture, and yet neat and attractive in appearance.

15 In the drawings forming part of this specification, Fig. 1 is a side sectional elevation of a soap serving means embodying my improvements. Fig. 2 is a perspective view of a portion of my preferred supporting means. Fig. 3 is a face view of a part of the supporting means.

20 As shown in Fig. 1, the receptacle 1 is preferably cylindrical in form, being composed of sheet metal coated with white enamel for the sake of attractiveness in appearance. The top 2 of this receptacle is centrally raised and provided with a filling 25 mouth 3, the cap 4 therefor being made of a larger interior diameter having a plurality of inward projections 5 fitting the mouth 3 friction tight. These projections serve both to firmly retain the cap in place, and at the same time to provide entrance for air to enter the receptacle.

25 The delivery device comprises a plunger 6 loosely slidable through an opening 7 in the floor 9 of the chamber 10. This opening is formed with an upwardly projecting flange 11 between which and the chamber wall is located a washer 12. On the plunger 6 is fastened an inverted cup 13 whose edge 14 is elastically pressed into liquid-tight engagement with the washer 12 by a helical spring 15 located on the plunger between the cup 13 and a partition-floor 16. The latter having a small hole 17 for ensuring the descent of the liquid soap into the chamber 10.

When the plunger 6 is pressed upward, as

by the application of the palm of the user's hand thereto, soap will descend past the plunger through the unoccupied space of the hole 7 into the hand.

60

For the support of this receptacle, a bracket is provided preferably composed of sheet metal and comprising an upright 20 having a hook 21 at its upper end for engaging a flange 25 at the upper edge of the receptacle, and an arm 22 at its lower end. Below this arm is a clamping member 23 having both ends turned up, the end 24 being adapted for engagement with the flange 25 at the lower end of the receptacle. The end 26 is formed with a shoulder 27, and between said ends is a hole for the reception of a screw 29 disposed for engaging an internally threaded hole 30 in the arm 22. By tightening this screw 29, the end 24 of the clamping member 23 and the hook 21 of the upright 20 are made tightly to grip the receptacle 1 between them and so hold it fast. The upright 20 is preferably made concave on its surface adjacent the receptacle so as 80 better to fit the same and to conceal the seam made in the manufacture of the same.

The base 30 of the bracket is provided with holes 31 through which to introduce fastening screws 32, and a pocket 33 having a slot 34 through the disk 30 immediately above the pocket. The arm 22 is formed with a foot 36 which is introduced through the slot 34 and then seated in the pocket 33 and fastened permanently therein by spot-welding. This gives both a firm and secure fastening, and a neat looking one as well.

From the upper part of the disc 30 a brace 37 extends to the upright 20, each end of the brace having a hand 39 fastened to the part 95 thereof by spot-welding.

After the parts have thus been put together they are preferably sprayed with white enamel and thereby made to look very clean and attractive in appearance.

100

Whenever it is desired to remove the receptacle 1 for refilling, washing or other purposes, all that is needed to be done is to turn the screw 29 sufficiently to permit the disengagement of the hook 24 from the lower 105 flange of the receptacle.

What I claim is:

1. A supporting bracket for a body having projecting rims at its top and bottom, comprising an upright having at one end a hook 110 engaging one of said rims and an arm at its other end, a clamping member having at

- one end a hook engaging the other rim of said receptacle, its other end engaging said arm, and a screw passing through said clamping member and tapped into said arm.
- 5 2. A supporting bracket for a body having projecting rims at its top and bottom, consisting of an upright having a hook at its upper end engaging a rim of said receptacle and having an arm projecting from its lower end, said arm having a transverse slot and a threaded hole,

a clamping member having a shouldered neck at one end entering said slot and a hook at its other end engaging the other rim of said receptacle, a plate attached to said arm, and a brace terminally attached to said plate and upright.

In testimony that I claim the foregoing invention, I have hereunto set my hand this 31st day of December, 1919.

HENRY P. UPHAM.
